UNITED STATES PATENT OFFICE

THOMAS RAYMOND ARDEN, OF BALDWIN, NEW YORK, ASSIGNOR TO AMERICAN FLYER MANUFACTURING COMPANY, OF CHICAGO, ILLINOIS, A CORPORATION OF ILLINOIS

ELECTRIC CLOCK

Application filed December 30, 1930. Serial No. 505,607.

This invention relates to electric clocks of the synchronous motor type, and has special reference to a clock of this type embodying a novel alarm mechanism. However, the present clock is complete in itself to the exclusion of the alarm mechanism, and in that connection an important object of the invention is to provide a construction which is greatly simplified, considerably more compact and 10 of materially lower production cost as compared with existing clocks of the same general type. Also, in this connection, another object of the invention is to provide a clock mechanism which may be constructed as a 15 unit to be used with clock faces or dials of various different diameters.

Another important object of the invention is to provide an alarm mechanism which may readily be rendered operative or inoperative 20 at will and which is effective, when set to produce an alarm at any given time, to repeat the alarm at the same time each succeeding twenty-four hours.

The present clock is of the type which requires manual starting. That is to say, whenever the current is turned off for any reason with consequent stopping of the clock, it is necessary to manually start or initiate operation of the clock when the current is again 30 turned on, and in this connection another important object of the invention is to provide means automatically operable to close the alarm circuit upon stopping of the clock, as for example, when the current is turned off, 35 whereby the alarm will sound when the current again is turned on, and continue to sound until the clock is started. In this way the alarm obviously serves as a warning means to indicate that resetting of the clock is necessary.

According to the present invention, the alarm, when set into operation during the normal operation of the clock, will continue to sound over an extended period of time, unless the operation thereof is manually interrupted, and in this connection another important object of the invention is to provide means whereby the alarm circuit, following 45 automatic closing thereof by normal operation of the clock, may readily be opened to

stop the sounding of the alarm, without disturbing the setting of the latter.

Another object of the invention is to provide a novel clock casing which may readily be disassembled to expose the operating mechanism of the clock, and is readily assembled to enclose the operating mechanism. 55

With the foregoing and various other objects in view, which will become more fully apparent as the nature and the advantages of the invention are more fully understood, the same consists in the various novel features of construction, and in the novel combinations and arrangements of parts, as will be hereinafter more fully described, illustrated in the accompanying drawings and defined in the appended claims. 60

In the drawings, wherein like characters of reference denote corresponding parts in the different views:— 70

Figure 1 is a front elevation of a clock constructed in accordance with one practical embodiment of the invention.

Figure 2 is a side elevation with the side and back of the casing removed. 75

Figure 3 is a rear elevation with the back of the casing removed.

Figure 4 is a top plan view with the side and the back of the casing removed.

Figure 5 is a central longitudinal section 80 through the clock showing the normal relative disposition of the parts of the alarm mechanism.

Figure 6 is a fragmentary longitudinal section showing the relative disposition of 85 the switch actuating parts of the alarm mechanism during sounding of the alarm.

Figure 7 is another view similar to Fig. 6 showing the relative disposition of the switch actuating parts of the alarm mechanism upon actuation of the means for manually stopping the sounding of the alarm. 90

Figure 8 is a vertical transverse section on the line 8—8 of Fig. 2.

Figure 9 is a vertical transverse section on 95 the line 9—9 of Fig. 2.

Figure 10 is a horizontal section on the line 10—10 of Fig. 3.

Figure 11 is a perspective view of the main 100 frame element of the clock.

Figure 12 is a detail section on the line 12—12 of Fig. 5.

Figure 13 is a similar detail section on the line 13—13 of Fig. 7.

5 Figure 14 is a detail perspective view showing the manner of slidably non-rotatably connecting a pair of the alarm actuating elements with one another; and

10 Figure 15 is a diagram of the motor and the alarm circuits.

Referring in detail to the specific embodiment of the invention illustrated in the drawings, it will be observed that the present clock mechanism is constructed as a unit 15 separate from the clock casing and from the dial of the clock, and that said unit, therefore, is adapted for use with dials and casings of various different shapes and sizes.

A supporting frame for the various operating parts constituting the present 20 clock mechanism unit is designated generally as A and is inclusive in the present instance of a plate 10 having forwardly extending foot formations 11 for the reception of fasteners whereby the clock mechanism unit is, as aforesaid, readily adapted to be mounted on a dial element of any desired size or shape. Side plates 12, 12 are bent to extend rearwardly from the plate 10 and these side plates 25 are connected together at or near their rear edges by a transverse plate 13 which is disposed parallel to the plate 10. The said side plates thus are held rigidly in spaced relation by the transverse plate 13 and the frame as 30 an entirety is reinforced and stiffened.

A synchronous electric motor of known design is designated generally as B and includes essentially a stator or field element 14 and an armature or rotor 15, the field element 40 14 being of U-shape and having a winding 16 as is usual. The side plates 12, 12 of the frame A are provided at their rear ends with outwardly directed ears 17, and the field element 14 of the motor B is rigidly mounted 45 on said frame, at the rear thereof, by means of fasteners 18 which are passed through said field element and said ears.

Journalized in the plates 10 and 13 of the frame A is a shaft 19 which extends rearwardly through and beyond the U-shaped field element 14 of the motor B as shown. Mounted on this shaft for rotation with respect thereto is a sleeve 20 and to this sleeve is affixed the rotor 15. Also fixed to or 55 formed integrally with said sleeve is a drive pinion 21 which meshes with a spur gear 22 that is fixed to a shaft 23 carrying a worm 24. The shaft 23 is disposed parallel to the shaft 19 and, like the shaft 19, is journalized 60 for rotation in the plates 10 and 13 of the frame A, said shaft 23, for a purpose which will later appear, being provided at its front end with a disk 25 and, between said disk and the plate 10, with an enlargement or drum 65 formation 23a.

Disposed below and at right angles to the shafts 19 and 23 is a shaft 26 which is journaled for rotation in the side plates 12, 12 of the frame A and which has fixed thereto a worm wheel 27 which meshes with the worm 70 24. Carried by the shaft 26 is a worm 28 which meshes with a worm wheel 29 that is loose on the shaft 19 but which is frictionally coupled with said shaft by means of a friction disk 30 and cooperating coil spring 31. That is to say, the disk 30 is fixed to the shaft 19 and the worm wheel 29 bears at one side against the adjacent face of said disk, while the spring 31 is disposed between the other side of said worm wheel and a suitable abutment, such as a collar 32, that is fixed to the shaft 19, the said spring being under compression and thereby reacting from the abutment 32 to maintain the worm wheel in frictional driving engagement with the disk 30. 80 Thus, while rotation of the rotor 15 obviously is effective to produce rotation of the shaft 19, it is equally obvious that said shaft is capable of being rotatably adjusted manually independently of the gear connection 90 of said shaft with said rotor.

The shaft 19 carries the minute hand 33 of the clock, and the gear ratio between said shaft and the rotor 15 is such that said shaft makes one complete rotation during each hour of time, in which connection it is understood, of course, that the rotor 15 rotates at a fixed rate of speed as determined by the cycles of the alternating current employed 95 for operating the motor B.

The hour hand 34 of the clock is carried by a sleeve 35 which is mounted on the shaft 19 for rotation with respect thereto, and there is provided a gear connection between said shaft and said sleeve whereby said sleeve is caused to complete one complete revolution for each twelve revolutions of said shaft. This gear connection comprises a spur pinion 36 fixed to the shaft 19 and meshing with a spur gear 37 fixed to a shaft 38 which is journaled in the plate 10 of the frame A, and a spur pinion 39 formed on or fixed to the shaft 38 and meshing with a spur gear 40 formed on or fixed to the sleeve 35.

The pinion 36 constitutes an abutment on the shaft 19 engaging the rear face of the plate 10 of the frame A to prevent forward movement of said shaft relative to said frame, while between the abutment 32 on said shaft and the rear frame plate 13 is disposed a spring disk 41 which tends constantly to urge said shaft forwardly thereby to hold said shaft against any endwise looseness or play.

The foregoing mechanism in association with a suitable dial and casing, obviously constitutes a time-piece which is complete in itself and which is of extreme simplicity, due especially to the use of the shaft 19 both as the minute hand arbor of the clock and as a 130

support for the armature or rotor of the motor, since this arrangement obviously permits the use of an extremely simple gear connection between said rotor and said shaft.

5 The present synchronous motor B is of the type which requires manual starting, and in this connection a feature of the present invention resides in the provision of a novel inertia weight device to facilitate starting of said motor. The inertia weight itself is designated as 42 and is in the form of a disk 10 which is mounted loosely on a sleeve 43 for rotation with respect thereto. The sleeve 43 is suitably engaged over and fixed to the sleeve 20 and is provided at its outer end with a finger grip formation or knob 44 whereby manual rotation of the sleeves 20, 43 is adapted to be effected. A coil spring 45 is engaged frictionally on the sleeve 43 and 15 one end of this spring is suitably secured, as at 46, to the inertia weight 42, while the other end thereof is free. Thus, rotation of the sleeve 43 in one direction has a tendency to unwrap the coil spring 45 and to release 20 the same from said sleeve 43 whereby the latter is free to turn relative to the inertia weight, while rotation of said sleeve in the opposite direction has a tendency to wrap the spring tighter thereon and thus produce rotation of the inertia weight therewith. The 25 spring is coiled or wound about the sleeve in the direction of rotation of the rotor 15, and thus it follows that when the sleeves 20, 43 are manually rotated by means of the knob 44 in a direction to initiate rotation of the rotor 15 in the proper direction, rotation also is imparted to the inertia weight 42, with the result that the tendency of said weight to 30 continue rotating, when even rotation of the rotor 15 is interrupted because of the current impulses delivered thereto, soon causes the rate of rotation of the rotor to synchronize with the current impulses, whereupon 35 said rotor continues to rotate as long as current is supplied to the motor. In this connection it is pointed out that the diameter of the knob 44 is such that by the normal operation of gripping said knob between the fingers and twirling said knob in a normal 40 manner, the resulting rotary speed of the rotor 15 is approximately the same as the normal rate of speed at which said rotor turns, which is another feature of the present clock conducive to quick starting of the 45 motor thereof.

In order to provide a simple yet practical and efficient means of lubricating the shaft 19 where the sleeve 20 rotates thereon, the knob 44 is formed hollow to receive a quantity of felt or similar absorbent material 47. This material surrounds the shaft 19 and is soaked with oil which is delivered to and fed along the shaft in a manner which is apparent. On the inner end of said shaft is threaded or otherwise suitably mounted a

knob 48 to facilitate rotation of said shaft in setting the clock.

While the worms 24 and 28 may be of any suitable construction, it is preferred to form these worms by the simple expedient of 70 frictionally engaging coil springs over the respective shafts 23 and 26, as this not only is quite economical in itself, but permits the use of ordinary spur gears in lieu of specially formed worm wheels for cooperation with 75 said worms.

Referring now to the present alarm mechanism, 49 designates, generally, a solenoid which is inclusive of a winding 50 and a movable armature element 51 which is adapted 80 to be reciprocated by reason of current impulses in the winding 50 when said winding is energized by an alternating current. This solenoid is mounted on one of the side plates 12 of the frame A and a bell 52 is suitably 85 mounted with respect to the reciprocal armature element 51 so as to be struck by the latter as the same reciprocates.

Mounted in an ear 53 forming part of the frame A at the front thereof is a fixed contact 54, while carried by the upper end of an arm 55 for cooperation with said fixed contact, is a movable contact 56. The lower end portion of the arm 55 extends across one side of the enlargement or drum formation 95 23^a of the shaft 23 and has extending loosely therethrough, to either side of said shaft, a pair of pins 57, 57 which are secured to a block 58 that extends across the opposite side of said enlargement or drum formation. On the free ends of said pins are threaded 100 adjustment nuts 59, 59, respectively, and between these nuts and the adjacent face of the arm 55 are interposed coil springs 60 which serve in an obvious manner to maintain the arm 55 frictionally engaged against the drum formation 23^a. The direction of rotation of the shaft 23 is counterclockwise as viewed in Fig. 8, and since the arm 55 is disposed against the outer side of the drum 23^a, it follows that the tendency of the arm to rotate with the shaft, causes the contact 56 to be maintained against a stop 61 in spaced relation to the contact 54 during normal operation of the clock. On the other hand, it is apparent that because of the frictional connection of the arm 55 with the shaft 23, said arm is capable of being swung in a clockwise direction as viewed in Fig. 8 at any time during rotation of said shaft in 110 a counterclockwise direction to effect engagement of the contact 56 with the contact 54, and, moreover, it will be noted that a spring 62 is suitably arranged to tend constantly to swing said arm 55 in a direction 115 to engage the contact 56 with the contact 54, this spring being relatively light so that the contacts 56, 54 are maintained spaced by reason of the frictional engagement of the arm 55 with the drum 23^a during rotation of 120

the shaft 23, but being sufficiently strong to swing said arm to effect engagement of the contact 56 with the contact 54 should rotation of the shaft 23 cease.

- 5 The current supply wires for the motor B are designated as 63, 63, respectively, and they are connected, as usual, with the terminals of the field winding 16 of said motor. In addition, one of said wires is connected 10 by a conductor 64 with the contact 56 and the other of said wires is connected by a conductor 65 with one terminal of the solenoid winding 50, the other terminal of said solenoid winding being connected by a conductor 15 66 with the contact 54. Thus it is apparent that upon engagement of the contact 56 with the contact 54 the circuit of the solenoid 49 will be closed and an alarm will be sounded by reason of the solenoid plunger element 51 20 being reciprocated and striking the bell 52.

Referring now to the present novel means for effecting automatic closing of the alarm circuit at any desired time, it will be observed that a sleeve 67 is rotatably mounted 25 in the plate 10 of the frame A above the shaft 19, and that this sleeve has fixed thereto a spur gear 68 which is disposed in mesh with another spur gear 69 that is fixed with respect to the gear 40, the relative diameters of said 30 gears 68, 69 being such that the gear 68 is rotated one complete turn during two complete revolutions of the gears 40 and 69; i. e., the sleeve 67 is rotated one complete turn during each twenty-four hours.

35 Extending through the sleeve 67 is a shaft 70 on the front end of which is fixed a spur gear 71 which meshes with a spur gear 72 that is rotatably mounted on the hour hand sleeve 35. On a forwardly extending hub-like formation of the gear 72 is mounted the alarm set hand 73, setting of which may be effected by rotation of the shaft 70 as is apparent.

Also fixed to the shaft 70 is a collar 74 45 which is journaled in the plate 13 of the frame A and through the instrumentality of which the rear end portion of said shaft is supported by said frame, forward movement of said shaft being prevented by a flange on said collar engaging the rear face of said plate 13, and rearward movement of said shaft being prevented by engagement of the hub of the gear 71 with the gear 68, which latter is disposed against the front face of the plate 10.

50 The sleeve 67 extends a suitable distance rearwardly beyond the plate 10 and near its rear end has formed therein, at diametrically opposite points in the outer face thereof, a pair of transverse grooves 75, 75. Also 55 formed either integrally with said sleeve, or separate therefrom and suitably fixed thereto, is a disk 76 from the rear face of which projects a lug 77.

A sleeve 78 for cooperation with the sleeve 67 is slidably engaged at its forward end over

the rear end portion of said sleeve 67 and at its rear end is slidably engaged on the shaft 70. This sleeve 78 is suitably splined at its rear end to the collar 74 whereby it is longitudinally slideable but non-rotatable relative to said collar and said shaft 70, and at its forward end carries a disk 79 having an annular forwardly extending marginal flange 80 in which is formed a notch 81 to receive the lug 77 of the disk 76.

70 A transverse, horizontal shaft 82 is journaled at its ends in the side plates 12, 12 of the frame A, and on this shaft is mounted a plate 83 for forward and backward rocking movement, said plate 83 extending upward from said shaft 82 and having portions thereof disposed in an annular groove 84 formed in the sleeve 78 whereby sliding movement of said sleeve is adapted to rock said plate and whereby rocking movement of said plate is adapted to effect sliding movement of said sleeve.

75 A pin 85 is mounted at its forward end in a top portion of the front plate 10 of the frame A and extends rearward loosely through an opening in the plate 83 and at or near its rear end carries an abutment 86 between which and the rear face of the plate 83 is interposed a light coil spring 87 which tends constantly to rock the plate 83 forwardly.

80 Projecting laterally and forwardly from the plate 83 is a finger 88 which extends across the switch arm 55 and is normally spaced slightly therefrom, but which is adapted, upon a certain amount of forward rocking movement of the plate 83, to engage said switch arm and to exert a cam or wedging action thereon to swing the upper end of the same toward the fixed contact 54, thus to engage the contact 56 with the contact 54 and close the alarm circuit.

85 Carried by the disk 79 is a U-shaped spring 89 the arms 90, 90 of which contact normally with the outer face of the sleeve 67 at diametrically opposite points thereon and have a constant tendency to spring inward, whereby, when said arms become alined with the grooves 75, 75 in said sleeve 67, they are 90 adapted to spring into said grooves.

95 The grooves 75, 75 extend transversely across the sleeve 67 in a direction at right angles to a radial line passing through the lug 77 of the disk 76, while the arms 90, 90 of the spring 89 extend transversely across the disk 79 in a direction at right angles to a radial line passing through the notch 81 in the disk 79. Consequently, assuming that the arms 90, 90 of the spring 89 are disposed in the same transverse plane as the grooves 100 75, 75, it is apparent that said spring arms will snap into said grooves when, by relative rotation of the sleeves 67 and 78, the lug 77 and the notch 81 are alined or approximately alined with one another, and that 105 110 115 120 125 130

when said spring arms are disposed in said grooves, relative rotation between the sleeves 67 and 78 will gradually force said spring arms outward relative to one another until 5 they will be disposed entirely out of said grooves when the lug 77 and the notch 81 are disposed at an angle of ninety degrees or approximately ninety degrees apart.

With the clock in normal operation and 10 the contact 56 spaced from the contact 54, the normal position of the plate 83 and the sleeves 67, 78 is as shown in Fig. 5 of the drawings. That is to say, the lug 77 and the notch 81 are disaligned with respect to one another, the sleeve 78 is held against being moved forward under the influence of the spring 87 by engagement of the forward edge of the flange 80 with the lug 77, and the spring arms 90, 90 are disposed in embracing relation to the sleeve 67 forwardly of the grooves 75, 75 in said sleeve. Now, since the plate 83 must rock forwardly from its foregoing position in order to permit the finger 88 of said plate to engage with and move the switch 25 arm 55 to engage the contact 56 with the contact 54 to close the alarm circuit, and since said plate 83 is held against forward movement by the engagement of the forward edge of the flange 80 with the lug 77, it follows 30 that the angular position of the disk 79 determines the time when the alarm circuit will automatically be closed, as the sleeve and disk 78-79 and consequently the plate 83 may move forward only when the lug 77, by 35 rotation of the disk 76, comes into alignment with the notch 81 in the disk 79, it being understood, of course, that the combined sleeve and disk 78-79 is not rotatable except manually to effect setting of the alarm, i. e., 40 to predetermine the time when the alarm shall begin to sound.

By following through the train of gearing between the motor B and the sleeve 67, it will be noted that said sleeve and the disk 76 carried thereby rotate in a clockwise direction 45 as viewed from the rear of the clock. Therefore, due to the frictional engagement of the lug 77 of said disk with the forward edge of the flange 80 of the disk 79, rotation of the 50 disk 76 obviously tends to effect rotation of the disk 79 therewith. If the disk 79 moved with the disk 76 the lug 77 would never become alined with the notch 81 and forward rocking movement of the plate 83 could never 55 take place. It is essential, therefore, that the sleeve and disk 78-79 be held against rotation by the disk 76 and it is equally essential that said sleeve and disk 78-79 be rotatably adjustable manually in order to predetermine 60 the time when forward movement of said sleeve and disk may occur. Thus, there is provided in the present instance a friction grip member 91 in the form of a length of 65 spring wire which is anchored at one end to the plate 13 and which is coiled about the

shaft 70, the other end of said wire being free. Said wire is coiled about said shaft in a clockwise direction as viewed from the rear of the clock whereby said shaft is held effectively against clockwise rotation as viewed from the rear because of the fact that any tendency of the shaft to rotate in a clockwise direction results in tendency of the wire coil to wrap tightly on the shaft and bind thereagainst. On the other hand, the shaft is more or less freely rotatable in the opposite direction because this tends to unwrap the wire coil and to release the frictional grip of the coil on the shaft. Moreover, in this connection, it will be observed that the thumb nut 92 that is provided on the rear end of the shaft 70 for effecting rotative adjustments of said shaft, is connected with said shaft by a left-hand thread, so that any effort to rotate said shaft in a right-hand direction by means of said nut will simply result in the nut being disengaged from the shaft.

To mount the clock mechanism on a dial 93 of any desired size or shape, the ears 11 of the frame A are disposed against the rear face of the dial and screws or other suitable fasteners 94 are passed through apertures in the dial and are either threaded into said ears or are passed through openings in said ears and have nuts threaded thereon to clamp the frame to the dial.

In the present instance, the dial 93 is of dished construction and directly carries the clock face indicia, but, as will be understood, this indicia may be carried by a sheet of paper or the like pasted or otherwise suitably secured against the outer face of the dial. The shaft 19, the sleeve 35 and the hub portion of the gear 72 extend through a central opening in the dial and the minute and hour and alarm set hands 33, 34 and 73 are mounted on said shaft, sleeve and hub portion, respectively, at the front side of the dial as is, of course, understood.

By reason of the dished form of the dial element 93, the dial portion proper thereof is disposed rearwardly of a lateral flange 95 defining the front portion thereof, whereby a recess or chamber is afforded between the front and rear portions of the dial for the accommodation of the hands 33, 34 and 73.

The clock casing preferably is constructed of sheet metal and is inclusive of a base 96, a front finishing plate 97, a rear closure plate 98 having apertures through which the shafts 19 and 70 extend, whereby the finger grip elements 44, 48 and 92 are accessible from the rear of the casing, and a one-piece side plate 99. The base 96 is provided with slots 100 to receive fingers 101 on the bottom edges of the front, rear and side plates, and the front and rear plates are provided with inwardly opening marginal grooves 102 to re-

ceive the front and rear edge portions of the side plate, respectively.

The front plate is provided with a relatively large opening whereby the dial 93 and the hands of the clock are visible, and the flange 95 of the dial 93 is disposed against the rear face of said front plate in surrounding relation to the opening therein as shown, the clock mechanism as an entirety being assembled with the front plate by suitable clamps 103 connected by screws or other fasteners with the front plate and engaging the rear face of the flange 95. Between the inner edge portion of the flange 95 and the marginal portion of the front plate surrounding the opening therein, is disposed a sheet of glass or other transparent material 104 which serves as a closure to protect the hands of the clock and to exclude dust from the dial.

Carried by and extending rearwardly from the front plate 97, above the dial 93, is member 105 which is of tubular formation at its front end and which is provided with a threaded lug formation 106 at its rear end, and which, intermediately, is provided with a slot or opening 107 in which is disposed an upward extension 108 of the rock-plate 83.

In assembling the casing elements 97, 98 and 99 with the base plate 96, the front plate first is assembled with the base plate by engaging the fingers 101 of said front plate in the slots 100 at the front of the base plate, the side plate 99 then is placed in position with its front edge disposed in the groove 102 of the front plate and with its fingers 101 engaged in related slots 100 in the base plate, and the rear plate 98 then is placed in position with its groove 102 receiving the rear edge of the side plate. A screw member 106' then is passed through an opening in the rear plate into threaded engagement with the lug 106 of the member 105 to draw the front and rear plates into clamping engagement with the side plate and the casing elements thus are secured in firm assembly with one another.

In the front tubular portion of the member 105 is slidably mounted a pin or rod 109, the front end of which extends through the front plate 97 and is equipped with a button 110 for finger manipulation, and the rear end of which is disposed for engagement with the upward extension 108 of the rock-plate 83. This rod 109 carries a radial pin 111, and the member 105 has a shoulder 112 behind which said pin 111 may be engaged by rotation of said rod 109 when the latter is pressed inward, thereby to lock said rod against outward movement, and when said pin is disposed behind said shoulder, the inner end of the rod 109 is disposed in engagement with the extension 108 of the rock-plate 83, holding the latter in its rearmost position. Thus, whenever desired, the alarm may be rendered

inoperative by a simple manipulation of said rod 109.

On the face of the dial 93 is a circular scale element 113 which is divided into twenty-four main divisions representing the twenty-four hours of a day, twelve o'clock noon being indicated at the top of said scale element, twelve o'clock midnight being indicated at the bottom of said scale element, and the numerals 1 to 11 being provided intermediate said noon and midnight indications, reading, respectively, downward from the right of the noon indication and upward from the left of the midnight indication, P. M. time being indicated by the left-hand half of the scale element and A. M. time being indicated by the right-hand half of the scale element. The alarm set hand cooperates with this scale element 113, and since the disk 76 completes only one-half of a complete revolution for a complete revolution of the hour hand 34, it follows that means must be provided as a guide for setting the alarm mechanism so that the alarm will not sound at a P. M. hour when it is intended to set the alarm to sound at an A. M. hour, and vice-versa. In this connection it will be observed that the dial 93 is provided with a hole 114 and that the gear wheel 71 also is provided with a hole, 115, for registration with the hole 114 once during each complete revolution of said gear wheel. The hole 115 in the gear wheel is disposed diametrically opposite the notch 81 in the disk 79, and when the hole in the gear wheel is alined with the hole in the dial, the alarm set hand 73 points to the twelve o'clock noon indication of the scale 113, which is always true due to the one-to-one gear ratio between the gears 71, 72. On the front face of the gear wheel 68 is an index element 116 which preferably takes the form of a spot of red paint or the like, and this index element is so positioned on said gear wheel 68 as to be visible through the alined holes 114, 115, only when the hands of the clock indicate twelve o'clock and the lug 77 is alined or substantially alined with the notch 81. Thus, by setting the alarm set hand to point to twelve o'clock noon, and by then setting the hands of the clock to point to twelve o'clock noon with the index element 116 visible through the alined holes 114, 115, a starting point is had from which the alarm set hand may be adjusted with assurance that the alarm will sound according to P. M. or A. M. time that may be desired.

As heretofore stated, the shaft 70 is rotatable in only a single direction, and thus, if an initial status of the alarm set mechanism is established as set forth in the foregoing, there is no possibility of effecting an erroneous adjustment of the disk 79 to permit the alarm to sound at a P. M. hour for

example when an A. M. hour was intended, or vice-versa. In the absence of means such as have just been described, a person in setting the alarm could not ascertain whether the alarm would sound at the P. M. or the A. M. hour indicated, since the lug 77 may be disposed either in alinement with the notch 81 or diametrically opposite said notch when the clock hands indicate twelve 10 o'clock and the alarm set hand points to twelve o'clock noon.

In view of the foregoing it is believed that the operation of the alarm mechanism will be clearly understood. Assuming that the motor B is in operation and that the movable contact 56 is held spaced from the contact 54 by reason of the frictional engagement of the enlargement 23^a of the shaft 23 on the switch arm 55 as heretofore 15 explained, and that the lug 77 and the notch 81 are disaligned, with the front edge of the flange 80 of the disk 79 disposed against the lug 77 and being urged forwardly thereagainst by the spring 87 acting through the 20 plate 83, (Fig. 5) it will be observed that under these conditions the U-shaped spring 82 carried by the disk 79 is disposed forwardly of the grooves 75, 75 in the sleeve 67 so that the sleeve and disk 78-79 are free 25 to move forward under the influence of the spring 87 when the lug 77 moves into alinement with the notch 81. Thus, when the lug 77 moves into alinement with the notch 81, the rock-plate 83 is swung forward by the spring 86 (Fig. 6) and automatic closing 30 of the alarm circuit is effected by reason of the consequent engagement of the finger 88 of the rock-plate with the switch arm 55 and the resulting swinging movement of said 35 switch arm in a direction to bring the contact 56 thereof into engagement with the contact 54. Upon closing of the alarm circuit, the alarm begins to operate and will continue to operate over a considerable period of time, 40 unless manually stopped, as determined by the amount of angular movement of the disk 76 which is necessary to disalign the lug 77 from the notch 81 and to force the disk 79 rearwardly to its initial position, it being 45 pointed out in this connection that the lug 77 and the notch 81 are of wedge shape so that continued rotation of the disk 76 when the lug 77 thereof is disposed in the notch 81, will result in the disk 79 being forced rearwardly. 50

As has previously been mentioned, the arms 90, 90 of the spring 89 extend in the same direction as the grooves 75, 75 in the sleeve 67 when the lug 77 and the notch 81 are alined. 55 Consequently, if the combined sleeve and disk 78-79 is shifted rearwardly a sufficient amount to aline the spring arms 90, 90 with the grooves 75, 75 in the sleeve 67 following forward, alarm circuit closing movement of 60 said sleeve and disk 78-79 while the lug 77

and the notch 81 are alined or approximately alined with one another, the said spring arms will snap into said grooves (Fig. 7) and the rock-plate 83 will thus be latched in a rearwardly swung position in which the finger 88 thereof is removed from the switch arm 55. And since said switch arm will be swung by its frictional engagement with the enlargement 23^a of the shaft 23 to disengage 70 the contact 56 from the contact 54 immediately following removal of the finger 88 from said switch arm, it follows that after the alarm begins to sound the same may be stopped manually simply by pressing the plate 83 rearwardly and without affecting the 75 capability of the alarm mechanism to again produce an alarm at the same hour during the next twenty-four hour period, since continued rotation of the sleeve 67 obviously, will result, after the elapse of a certain amount of 80 time during which the lug 77 has become disaligned from the notch 81, in the spring arms 90, 90 being gradually spread apart because of the oblong cross section of the sleeve 67 in the plane of the grooves 75, 75 until said arms 85 are forced outwardly entirely free of said grooves, whereupon the sleeve 78 will spring forward under the influence of the spring 87 to its initial position with the forward edge 90 of the flange 80 thereof in engagement with the lug 77, in readiness to move farther forward to effect automatic closing of the alarm 95 circuit when the lug 77 again alines with the notch 81. Thus, following automatic closing 100 of the alarm circuit, and if sounding of the alarm is not manually stopped as just described, the alarm may continue to sound over an extended period of time, whereupon it will automatically stop while on the other hand, it is obvious that the sounding of the 105 alarm may be manually stopped at any time during the normal alarm period.

The rod 109 affords means for effecting inward movement of the plate 83 to cut off the alarm, in which connection it is pointed out 110 that the pin 111 carried by said rod is engaged behind the shoulder 112 only when it is desired to lock the plate 83 against forward movement as, for example, when it is desired to use the clock without using the 115 alarm mechanism thereof.

In order that a person may readily ascertain at a glance whether the clock is operating, the front face of the disk 25 on the shaft 23 may be variably colored, and an 120 opening 118 may be formed in the dial 93 through which the front face of said disc is visible, the passage of the differently colored portions of said disk across the opening in the dial affording a ready means of determining 125 whether the shaft 23 is rotating.

Without further description it is thought that the features and advantages of the invention will be readily apparent to those skilled in the art, and it will of course be un- 130

derstood that changes in the form, proportion and minor details of construction may be resorted to, without departing from the spirit of the invention and scope of the appended claims.

5 I claim:—

1. In an electric clock, an alarm circuit inclusive of a switch and an electric alarm device, movable clock operated means operable by movement thereof to hold said switch normally open, clock operated means for closing said switch during operation of the clock and against the tendency of said first mentioned means to hold the switch open, 10 and means for adjusting said last named means to predetermine the time of closing of said circuit by operation of the clock.

2. In an electric clock, a synchronous motor of the type requiring manual starting, 20 a motor circuit, an alarm circuit connected with the motor circuit and inclusive of a switch and an electric alarm device, means whereby operation of the motor maintains said switch normally open, means operable 25 automatically to close said switch upon stopping of the motor, clock operated means for closing said switch during operation of the motor, and means for adjusting said last named means to predetermine the time of 30 closing of said switch by operation of the clock.

3. In an electric clock, an alarm circuit inclusive of a switch and an electric alarm device, movable clock operated means operable 35 by movement thereof to hold said switch normally open, and means operable by the clock to temporarily close said switch once only and at the same time during each successive period of twenty-four hours.

40 4. In an electric clock, an alarm circuit inclusive of a switch and an electric alarm device, movable clock operated means operable by movement thereof to hold said switch normally open, means operable by the clock to 45 temporarily close said switch once only and at the same time during each successive period of twenty-four hours, and means for adjusting said last named means to predetermine the time of closing of the switch.

50 5. In an electric clock, an alarm circuit inclusive of a switch and an electric alarm device, movable clock operated means operable by movement thereof to maintain said switch normally open, means operable by the clock to 55 temporarily close said switch at predetermined times, means for manually moving said second mentioned means to a switch releasing position following closing of the switch by said second mentioned means, and means operable upon movement of said second mentioned means to switch releasing position to temporarily maintain the same in such position without affecting the capability 65 of said second mentioned means to be oper-

ated by the clock to close the switch at a predetermined time.

6. In an electric clock a rotatable member, an electric alarm device, a switch in controlling relation to said alarm device, said switch being inclusive of a fixed contact and a movable contact, means constantly tending to move said movable contact into engagement with said fixed contact to close the alarm circuit, and a friction connection between said movable contact and said rotatable member whereby rotation of the latter maintains the switch normally open during operation of the clock. 70

7. In a clock, a clock mechanism, an electric alarm device, a switch in controlling relation to said alarm device, means responsive to movement of a part of the clock mechanism to maintain said switch normally open, a member movable to effect closing of said switch during movement of said part of said clock mechanism, means tending constantly to so move said member, restraining means for said member and clock operated means in controlling relation to said restraining means. 80

8. In a clock, a clock mechanism, an electric alarm device, a switch in controlling relation to said alarm device, means responsive to movement of a part of the clock mechanism to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first mentioned member and which, when aligned, permit axial movement of said second mentioned member toward said first member, and a switch closing element controlled by said second mentioned member. 90

9. In a clock, a clock mechanism, an electric alarm device, a switch in controlling relation to said alarm device, means responsive to movement of a part of the clock mechanism to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first 100 member and which, when aligned, permit axial movement of said second mentioned member toward said first member, and a switch closing element controlled by said second mentioned member. 105

115 10. In a clock, a clock mechanism, an electric alarm device, a switch in controlling relation to said alarm device, means responsive to movement of a part of the clock mechanism to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first 120 member and which, when aligned, permit axial movement of said second mentioned member toward said first member, and a switch closing element controlled by said second mentioned member, means tending con- 125 130

stantly to move said second mentioned member axially toward said first mentioned member, and means for latching said second mentioned member against axial movement toward said first mentioned member when the lug and recess formations of said members are alined with one another.

10. In a clock, a clock mechanism, an electric alarm device, a switch in controlling relation to said alarm device, means responsive to movement of a part of the clock mechanism to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first mentioned member and which, when aligned, permit axial movement of said second mentioned member toward said first member, means tending constantly to move said second mentioned member toward said first member, a switch closing element controlled by said second member, an alarm set hand, and a connection between said second mentioned member and said alarm set hand whereby rotation of said second mentioned member effects adjustment of said alarm set hand.

Justment of said alarm set hand.

11. In a clock, a clock mechanism, an electric alarm device, a switch in controlling relation to said alarm device, means responsive to movement of a part of the clock mechanism to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first mentioned member and which, when aligned, permit axial movement of said second mentioned member toward said first member, a switch closing element controlled by said second mentioned member, means tending constantly to move said second mentioned member axially toward said first mentioned member, means for releasably latching said second mentioned member against axial movement toward said first mentioned member when the lug and recess formations of said members are aligned with one another, and means whereby a predetermined amount of relative rotation between said members effects automatic release of said latching means.

12. In a clock, a clock mechanism, an electric alarm device, a switch in controlling relation to said alarm device, means responsive to movement of a part of the clock mechanism.

to maintain said switch normally open, a pair of rotatable members one of which is connected with the clock mechanism to be rotated thereby during operation of the clock and the other of which is manually rotatably adjustable and mounted for axial movement relative to the first member, cooperating lug and recess formations on said members which, when disaligned, limit axial movement of the second mentioned member toward the first mentioned member and which, when aligned, permit axial movement of said second mentioned member toward said first member, a switch closing element controlled by said second mentioned member, and manually operable means for locking said switch closing element against switch closing movement.

13. In an electric clock, an alarm circuit inclusive of a switch, movable clock operated means operable by movement thereof to hold said switch normally open, and clock controlled means for closing said switch during movement of said first mentioned means. 85

14. In an electric clock, a clock mechanism, an alarm circuit inclusive of a switch, means whereby movement of a part of the clock mechanism maintains said switch normally open during operation of the clock mechanism, clock controlled means for closing said switch at a predetermined time during movement of said first mentioned means, and means constantly tending to close said switch and effective upon stopping of the clock to close said switch. 90 95

15. In an electric clock, an alarm circuit inclusive of a switch, rotatable clock operated means operable by rotation thereof to maintain said switch normally open, and clock controlled means for closing said switch during rotation of said first mentioned means. 105

16. In an electric clock, a clock mechanism, an alarm circuit inclusive of a switch, means whereby rotation of a part of the clock mechanism maintains said switch normally open during operation of the clock mechanism, clock operated means for closing said switch, during rotation of said first mentioned means, and means effective upon stopping of the clock to close said switch. 110

17. In an electric clock, a clock mechanism, an alarm circuit inclusive of a switch, means whereby movement of a part of the clock mechanism maintains said switch normally open, and clock operated means effective to temporarily close said switch at a predetermined time and to repeat temporary closing of said switch once only and at the same time during each succeeding period of twenty-four hours during continuous operation of the clock.

18. In an electric clock, a clock mechanism, an alarm circuit inclusive of a switch, friction means rendered effective by movement of a part of the clock mechanism to maintain said switch normally open during normal op- 130

eration of the clock, and clock operated means for closing said switch.

19. In an electric clock, a clock mechanism, an alarm circuit inclusive of a circuit closer, 5 friction means rendered effective by movement of a part of the clock mechanism to maintain said circuit closer normally open during normal operation of the clock, clock operated means for closing said circuit closer

10 at a predetermined time, and means constantly tending to close said circuit closer whereby upon the current to the clock being cut off with consequent stopping of the clock the alarm circuit is closed to be energized 15 when current again is supplied to the clock.

20. In an electric clock, a clock mechanism, an alarm circuit, a switch in said alarm circuit inclusive of a fixed contact and a movable contact, friction means whereby move-

20 ment of a part of the clock mechanism maintains said movable contact normally spaced from said fixed contact, and clock controlled means for moving said movable contact into engagement with said fixed contact against 25 the action of said friction means.

21. In an electric clock, a clock mechanism, an alarm circuit, a switch in said alarm circuit inclusive of fixed and movable contacts, means responsive to movement of a 30 part of the clock mechanism during normal operation of the clock to hold said movable contact spaced from said fixed contact, means constantly tending to move said movable contact into engagement with said fixed

35 contact and effective upon stopping of the clock to move said movable contact into engagement with said fixed contact to close the circuit, and clock controlled means effective during normal operation of the clock

40 to overcome the means holding said movable contact spaced from said fixed contact and to move the former contact into engagement with the latter contact.

22. In an electric clock, a clock mechanism, an alarm circuit, a single normally 45 open switch in said circuit, means responsive to operation of the clock to maintain said switch normally open during operation of the clock, means constantly tending to 50 close said switch and effective to do so upon stopping of the clock, and other means under the control of the clock mechanism and effective during operation thereof to close said switch against the action of said first mentioned means.

23. In an electric clock, a clock mechanism, an alarm circuit inclusive of a switch, means whereby movement of a part of the clock mechanism maintains said switch normally open, means under the control of the clock mechanism operable to effect repeated temporary closing of said switch during movement of said movable part of the clock mechanism, and manually operable means to 65 open said switch following closing thereof

by said second mentioned means and to maintain said switch open without affecting the capability of said second mentioned means to close said switch at a predetermined time during continued operation of 70 the clock.

24. An automatically repeating electrical alarm clock including an electrically actuated alarm device, an electrical operating circuit therefor, a circuit-closing device included in said circuit, time-controlled mechanism for closing the circuit closing device and repeating such operation automatically at predetermined time intervals, and means for automatically closing the said circuit closing device upon stoppage of the current supply. 75 80

In testimony whereof I hereunto affix my signature.
